HYDRAULIC PUMP OR MOTOR

Elek K. Benedek, Bucyrus, Ohio

Application August 9, 1935, Serial No. 35,480

7 Claims. (Cl. 103—161)

This invention relates to hydraulic pumps and motors of the rotary, radial plunger type, employing rotary reactances, and particularly to pumps and motors of this character for use in connection with hydraulic transmission systems.

The principal object of the present invention is to provide a simplified, compact, and efficient, rotary reactance which may be manufactured and installed more economically than those heretofore employed and which is adapted for accuracy in manufacture by quantity production methods employing simple and well understood machining operations and standard tools and equipment.

Another object is to provide a rotary reactance having a very great working resistance radially for withstanding radial load as a result of which the axial dimension of the reactance can be reduced.

Another object is to provide a rotary reactance which is drivingly connected to the barrel of the pump or motor by the plunger actuating means in such a manner that separate or accessory mechanical coupling devices are eliminated.

A more specific object is to provide a plurality of axially floating rotary reactance rings and axially floating plunger actuating means which cooperate with the opposite ends of the plunger in a manner permitting elimination of accessory clamping means between the rings and permitting free but limited axial floating movement of the rings with respect to each other and to the plunger actuating means whereby the rings and actuating means are self-adjusting axially with respect to each other and to the cylinder barrel and plungers.

A correlative object is to provide a novel anti-friction mounting for the reactance.

Another object is to provide a flexible starting means between the plunger actuating means and the rotary reactance which means are rendered active to provide the driving connection by centrifugal force so as to effect a more gradual approach to synchronous rotation of the barrel and reactance, whereby noise and impact stresses from starting are reduced.

Another object is to increase the safety factor of pumps or motors with reference to the load and association of the various working parts so that failure of one part is not apt to cause displacement of such part or other parts and consequent break-down or failure of the pump or motor structure.

Still another object is to provide a rotary reactance, plunger actuating connection, barrel

and pintle mounting of such character that assembly and disassembly of the parts for repairs and inspection are greatly simplified and facilitated.

Another object is to provide a variable delivery motor having a large capacity ratio relative to the pump but with a sufficiently long stroke to provide greater flexibility in adjustment for effecting a wide range of speed, power and torque with high efficiency throughout the range.

Other objects and advantages will become apparent from the following specification wherein reference is made to the drawings in which

Fig. 1 is a horizontal sectional plan view of a hydraulic transmission mechanism embodying the principles of the present invention;

Figs. 2 and 3 are vertical cross sectional views taken on planes indicated by the lines 2—2 and 3—3 respectively of Fig. 1;

Fig. 4 is an enlarged sectional view of the rotary reactance used in connection with the present invention showing the rotary reactance as a sub-assembly; and is taken on a plane indicated by the line 4—4 in Fig. 5;

Fig. 5 is a sectional view of the reactance rotor subassembly of Fig. 4 and is taken on a plane indicated by the line 5—5 thereof;

Fig. 6 is a fragmentary sectional view similar to Fig. 4 illustrating a modified form of rotary reactance and is taken on a plane indicated by the line 6—6 of Fig. 7;

Fig. 7 is a sectional view of the rotary reactance illustrated in Fig. 6 and is taken on the plane indicated by the line 7—7 of Fig. 6;

Fig. 8 is a vertical sectional view through a stationary rotary reactance housing an associated rotary reactance illustrating another modification of the reactance;

Fig. 9 is a fragmentary sectional view taken on the plane indicated by the line 8—9 in Fig. 8;

Fig. 10 is a vertical sectional view through a stationary reactance housing and associated rotary reactance illustrating another modification of the reactance;

Fig. 11 is a fragmentary sectional view taken on the plane indicated by the line 11—11 on Fig. 10;

Fig. 12 is a fragmentary longitudinal central sectional view taken on a horizontal plane similar to that on which Fig. 1 is taken and showing a modified multiple plunger pump or motor employing the rotary reactance means of the present invention.

Fig. 13 is a fragmentary sectional view illus-

trating a novel anti-friction mounting for the rotary reactance.

For the purposes of illustration, the present invention is shown embodied in both a pump and a motor, the pump and motor being co-operated in a hydraulic transmission and both being of the rotary, radial plunger, reversible, variable displacement type. Both the pump and the motor are mounted in a casing, designated generally as 1, having a central valve portion 2 which terminates at its ends in radial flanges 3 and 4 respectively. The flanges, in turn, are provided at their outer margins with annular, axially extending walls 3a and 4a respectively, forming compartments for the pump and motor. The ends of the casing are closed by suitable rigid end covers 5 and 6 respectively which are bolted to the ends of the annular walls 3a and 4a so that a rigid unitary casing structure, in which all necessary axial bores and shoulders can be machined readily and coaxially for assembly in accurate alignment with each other, is provided. In the left hand compartment of the casing is mounted a pump, and in the right hand compartment is mounted a motor.

Referring first to the pump structure, the pump comprises a rotatable barrel 10 which has a coaxial impeller or drive shaft 10a, preferably forged integral with the barrel for purposes hereinafter set forth. The barrel is rotatably mounted in the casing portion 3a on coaxial sets of combination radial load and axial thrust anti-friction bearings 11 and 12 respectively. The sets of bearings 11 and 12, in turn, operate on inner races which are fixedly secured on hub or end portions of the barrel 10, as illustrated, and outer races which are fixedly secured against appropriate shoulders in the flange 3 and end cover 5 respectively. The outer races of the bearings 11 and 12 are such as to permit removal of the barrel axially consequent upon removal of the end cover 5. By drawing the end cover 5 to the desired position axially, employing shims between it and the end of the wall 3a the bearings 11 and 12 may be pre-loaded to the degree necessary to assure accurate positioning of the barrel and to compensate for wear.

On the barrel 10, between the hub portions, is a radial flange 14 which is preferably forged integral with the barrel and has smooth, polished, radially extending end walls. In the zone of the flange 14, the barrel has a plurality of circumferentially spaced radial cylinders 15, each of which cylinders is provided with a cylinder port 16 in communication with an axial valve bore of the barrel 10 for effecting valving cooperation with a valve pintle, later to be described. The flange 14 is provided with radial guide ways 17, each guideway being aligned and coaxial with an associated cylinder 15. The radially extending walls of the guideways 17, in advance of and to the rear of the associated cylinder, are cylindrical.

Mounted within each cylinder is a radial plunger 18, having at its outer end an enlarged crosshead 19, the crosshead having cylindrical front and rear walls snugly fitting the cylindrical walls of the guideways 17 for reciprocation therewith, the crosshead being prevented from movement endwise of the flange by the mating cylindrical surfaces.

The lateral faces of the heads 19 are smooth and polished so as to define, with the radial respective end walls of the flange, substantially continuous radial surfaces. Each of the heads 19

has a pin receiving bore which extends parallel to the axis of rotation of the barrel and in which is received a journal or crosspin 20. The pin 20 extends beyond the lateral limits of the crosshead in each direction, the extending portions 20a being of less diameter than the central portion and being in cooperation with the rotary reactance 22 for reciprocating the associated piston. Suitable rounded shoulders 20b are provided between the central and end portions of the pins for engagement with the rotary reactance for purposes hereinafter set forth. The pins 20 are rotatably supported in their associated crosshead bores on suitable capillary cageless needle rollers 21, the ends of the bores being closed by suitable retaining washers for maintaining the rollers in position axially of the bore. In this manner the pins may float axially relative to the associated crosshead and resistance to rotation of the pins in the crossheads is less than between the pin 20 ends and rotary reactance, thus assuring rolling load transmission.

For actuating the plunger through the medium of the pin ends 20a, coaxial rotary reactance rings 22 are provided. It is necessary for economy in manufacture and to meet commercial competition, that the rotary reactance be simple, compact, and durable, that they be of such form that they may be manufactured accurately and economically, that they be so associated with the plungers that ease and accuracy in assembly and disassembly are assured. In addition, the reactance must be capable of withstanding severe radial loads, must cooperate efficiently and accurately with the plungers at all times, and must be of reasonable dimension axially.

For meeting these requirements, each of the rings 22 is preferably of rectangular cross section having parallel radially extending end faces which are hardened and accurately polished as also is the outer circumferential wall. Two such rings are provided, one at each end of the barrel flange, and the rings are disposed with their adjacent end faces in substantially face to face relationship with the end faces of the flange 14, operating clearance only being provided between the flange and rings for permitting the entrance of slip fluid therebetween. The rings are rotatably mounted in a suitable housing later to be described, for rotation about an axis parallel to, but offset from, the axis of rotation of the barrel 10. Each ring 22 is provided with a series of circumferentially spaced grooves 22a which extend endwise of the rings entirely therethrough, forming slots and may be arcuate, as illustrated, or chordal, depending upon the particular unit in which they are to be used. The grooves of each ring are aligned axially of the rings with respect to the grooves of the other and receive and snugly accommodate the reduced end portions of the pins 20.

The grooves 22a are preferably formed by boring spaced holes in each ring parallel to the ring axis, and then machining out the intervening material so that the ends of the grooves are arcuate and correspond accurately in radius to the radius of the reduced end portions 20a of pins. Thus smooth operation in starting and stopping is provided by proper seating of the pin ends against the cylindrical ends of the grooves.

The crosspin end portions 20a are of sufficient length to extend entirely through the grooves and slightly therebeyond past the outer end faces of the rings. As better illustrated in Fig. 5, these protruding end portions are recessed circumfer-

tially adjacent the plane of the outer end faces of the rings 22. Snap washers 23 are disposed in the recesses and accommodated therein with slight axial clearance and engage the end faces of the rings to constrain them from axial separation.

Since the pins 20 are mounted on capillary bearings 21 and may float axially in the bores of the crossheads, and since clearance is provided between the washers 23 and the rings 22, limited floating movement between the end portions of the pins and the rings is provided and both the rings and pins may adjust themselves axially to proper operating position with respect to each other and to the crossheads and barrel flange.

15 Due to the shoulders 20b, accurate minimum spacing of the rings axially is assured. This self-adjustment requires also that the rings 22 be mounted for axial floating movement in their supporting means.

For supporting the rings 22 in this manner, an adjustable reactance housing 24 coaxial with the rings, is mounted in the casing portion 3a. The housing 24 is supported in surrounding relation to both rings 22 and extends axially therebeyond. The portions of the housing 24 aligned radially with the rings are recesses circumferentially, as indicated at 24a. Sets of elongated free needle rollers 25 are accommodated in the recesses 24a, the recesses preferably being in depth substantially the same or slightly less than the diameter of the rollers 25 so that the end portions of the housing constrain the rollers from axial separation and form lubricant retaining troughs. In the form illustrated, two such sets of rollers are provided, one for each reactance ring respectively, though a single set of elongated rollers engaging both of the rings 22 may be utilized providing the length-diameter ratio remains less than ten.

40 The rollers 25 are first packed between the housing 24 and rings 22, and two or three rollers of each set are then removed so that the total clearance circumferentially of the housing 24 is only sufficient to provide capillary clearance between the individual rollers of each set, the rollers and arrangement thereof being more fully described in my United States Letters Patent No. 2,074,202, issued March 16, 1937.

In this mounting, the circumferential surface of each of the rings 22 is finished with great precision and hardened to withstand wear as above mentioned. The bottoms of the recesses in the housing 24 are likewise precisely finished and hardened so that accurate coaxial relationship between the housing recesses 24a and rings 22 is provided. Another advantage resides in this mounting of the rings in that slip fluid may pass between the rings 22 and crossheads and between all connected parts and into the recesses 24a where it is maintained as a pressure oil bearing by centrifugal force during the operation of the pump. However, upon stopping the pump, this centrifugal lubrication ceases. The rollers, however, though they may not be true capillary rollers, are constrained to circumferentially spacing of only a capillary distance apart from each other, as explained above. Consequently, although the entire space between the rollers and the race surfaces will not be filled with lubricant after the pump has stopped for an interval and the centrifugal pressure lubrication has ceased, nevertheless the space between the rollers themselves will maintain continuously capillary films of sufficient extent circumferentially of the individual rollers and especially be-

tween the adjacent surface portions of adjacent rollers, to insure proper lubrication until the centrifugal film is again replaced. By this arrangement, the rings 22 may float axially individually relative to the housing 23 and efficient lubrication is assured at all times.

In this structure, the rings must be very accurate and appreciable elastic deformation must be avoided. Consequently, the rings are sufficiently rigid radially to withstand heavy hydraulic loads and also stresses occasioned by heat treating and hardening all without deformation, as obviously, any such deformation would immediately be reflected in the outer circumferential wall which forms the raceway of 15 the rollers 25.

The rings 22 are, therefore, made radially deep and the grooves 22a are formed near the radial mid-portion or median, wherein the removal of material does not appreciably reduce the 20 strength of the rings.

The pump, as mentioned, is of the reversible variable delivery type and consequently the housing 24 must be mounted for adjustment to different positions wherein it is coaxial with or has its 25 axis disposed parallel to and offset from the axis of rotation of the barrel. For mounting the housing for adjustment, the casing portion 3a is provided with diametrically opposite parallel slide bearing surfaces 26, and complementary 30 slide bearing surfaces 27 are formed on the housing 24, these surfaces cooperating to support the housing accurately during adjustment.

Control rods 28 are secured on the housing and extend parallel to the slide bearing surfaces 35 26 and 27 through suitable bores in the casing, for adjustment of the housing and associated rings 22 from the outside of the casing.

In the right hand compartment of the casing, Fig. 1, is mounted the cylinder barrel 38 of the 40 motor, the barrel bearing being provided with a drive shaft 30a also forged integral with the barrel 30.

As described in my copending application Serial No. 31,651, filed July 16, 1935, there is a 45 definite relation between the efficiency and the stroke cylinder-diameter ratio of a pump or motor. Likewise, there is an increase in efficiency with an increase in size. When the stroke cylinder-diameter ratio is unduly decreased by 50 virtue of a large cylinder motor operating at very short stroke, the efficiency decreases rapidly. It is desirable, especially in a constant horsepower cycle transmission, that the motor have a large capacity relation to the pump so that 55 a small high speed pump may be used to supply the fluid pressure for a larger capacity motor which may operate at less speed but can withstand greater torque. In the present structure, assuming it is to be used for automobiles, a motor 60 employing a set of large cylinder and plunger assemblies might be used. This would have an objection at a short stroke, because the stroke cylinder-diameter ratio would then be greatly reduced and the efficiency correspondingly decreased.

In the present structure, therefore, a motor employing a multi-set of cylinders, for example, twin cylinders, is utilized, thus providing the 70 large capacity relative to the pump but at the same time affording greater efficiency in operation when the motor operates at shorter stroke, as obviously the stroke cylinder-diameter ratio does not decrease so rapidly with the twin cylinder- 75

ders as it would were a single equivalent large cylinder used.

In the illustrative motor structure, a twin plunger motor is utilized to meet the particular specific demand of speed and size. The barrel 30 conforms, in general, to the barrel of the pump and is mounted in the casing in anti-friction bearings 31 and 32 respectively corresponding to bearings 11 and 12. Intermediate its ends, the barrel has an integrally forged radial flange 34, and, in the zone of the flange, a series of circumferentially spaced, radial, twin cylinders 35. The cylinders are in communication with the valve bore of the barrel, later to be described, through suitable individual cylinder ports 36.

The twin cylinders 35 are arranged in pairs, the axes of the cylinders of each pair lying in the same radial plane through the axis of rotation of the barrel. In the flange 34 are radial guideways 37 corresponding in form and function to the guideways 17 of the pump.

Mounted in the cylinders 35 are plungers 38 having enlarged crossheads 39, respectively, which are reciprocable in and guided by the guideways 37. The plungers are correspondingly arranged in pairs, the crossheads of each pair of twin plungers preferably being in juxtaposition at their adjacent faces and having their outer faces terminating substantially in the respective planes of the end faces of the flange 34. The crossheads of each pair are provided with aligned pin receiving bores extending parallel to the axis of the barrel, for receiving a single thrust or journal pin 40, common to both heads and having reduced end portions 40a corresponding to the end portions 20a of the pump crosspin. Each crosspin 40 is rotatably mounted in the aligned bores of the crossheads on sets of capillary cageless needle rollers 41, the sets of rollers being spaced apart by suitable spacing washers, as illustrated. Retaining washers are also provided at the outer ends of the sets of needle rollers for retaining them within the bores of the associated plunger heads.

The plunger heads are so arranged and are of such width as to terminate at their outer limits, each substantially at or very close to the corresponding end face of the flange 34, and both the faces of the plunger heads and the end faces of the flange are hardened and accurately polished so as to present smooth radial faces to resist wear and to offer the slightest frictional resistance to any parts contacting therewith.

For actuating the twin plungers through the medium of the pins 40, a rotary reactance is provided, this rotary reactance comprising a pair of rings 42 corresponding in form and function to the rings 22 above described. The rings 42 are provided with circumferential grooves 42a corresponding to the grooves 22a of the rings 22, and in which are correspondingly received the reduced end portions 40a of the crosspins 40. The ends 40a of the crosspins extend outwardly beyond the ends of the rings 42 and are recessed to receive soap washers 43, the recesses being slightly greater in width axially of the pin than the thickness of the washers so as to provide free floating limited movement between the crosspins and the rings 42.

For rotatably supporting the rings for adjustment to different degrees of eccentricity relative to the barrel, a reactance housing 44 is provided and mounted in the casing 4a in a manner corresponding to the reactance housing 24. The

housing 44 is also recessed internally with circumferential recesses 44a in which are received free cageless rollers 45 spaced a capillary distance from each other in the same manner as the rollers 25, so that the rings 42 may float axially therein. For shifting the housing 44 to different adjusted positions, adjusting rods 48 are provided, these rods extending diametrically opposite from each other through suitable bores 48a in the casing portion 4a, the bores preferably being slightly greater in diameter than the rods so as to permit the rods to become self-aligning with respect to the housing 44.

Both the pins 20 and 40 are provided with slightly rounded wall portions at the juncture of their central and reduced end portions, as described in connection with the pins 20, and the groove edges of the associated rings 22 and 42 are correspondingly rounded, as best indicated in Fig. 5, thus providing cooperating shoulders on the pins and rings so that the rings are held in proper axial spaced relation with respect to each other by their associated pins and washers and, in turn, the rings cooperate with the end faces of the associated flanges for constraining the pins to proper axial position. Due to the particular manner of mounting the pins in the plunger heads anti-frictionally, the frictional resistance to rotation of the pins in the plunger heads is less than the rolling friction between the end portions of the pins and the associated groove walls, as set forth and claimed in my copending application, Serial No. 716,451, filed March 20, 1934, so that accidental sliding of the pins is eliminated.

Since, as stated above, the rods 48 may move slightly in the associated bores of the casing, and, since the outer peripheral walls of the rings 42 are mounted on rollers 45 for free axial floating movement, it is apparent that when the plungers are mounted within the barrel cylinders and connected to the rings by the pins 40 in the manner described, the rings 42 will properly align themselves therewith and with the rollers 45 of the housing 44, and at the same time, the housing 44 may accommodate itself to different axial positions of the rotary reactance mechanism. The radial walls of the flange portions 3 and 4 of the casing and of the end covers 5 and 6 are likewise finished accurately and smoothly and are positioned with slight axial clearance with respect to the corresponding ends of the pins 20 and 40, the housings 24 and 44, and the rings 22 and 42. Thus, in event any part of the reactance or of the crosspin assemblies becomes loosened or is broken, the parts will be constrained from falling out of place and damaging other working parts or wrecking the structure.

As a result of this arrangement, the extreme simplicity of the parts, and the very reduced number of parts, a very simplified, compact, efficient and safe structure is provided.

Before referring to the valving cooperation and fluid pressure system, certain advantages of the present structure should be specifically pointed out. In the first place the rings 22 and 42 are of the simplest possible design yet are of the preferred design for strength and durability permitting compactness both radially and axially. Due to their extreme simplicity they may be readily machined, hardened and polished and provided with suitable grooves in accordance with such standard practices that extreme accuracy may be provided economically. The crosspins likewise are simple and easily manufac-

tured. Next, the connection between the crosspins and the rings by virtue of the washers 43 is inexpensive and very positive. In addition to these advantages the axial floating relation rendering the parts self-adjusting adds materially to the life of the structure.

When thus assembled and connected by the crosspins, the rings and crosspins reinforce each other axially and provide a reinforced rotary reactance structure. Again, assembly and disassembly is rendered far more easy than heretofore and is reduced substantially to a minimum. For example, if it is desired to disassemble the pump, it is only necessary that the end cover 5 be removed, carrying with it the outer races of the bearings 11. Ready access is then afforded to the snap washers 23 adjacent the end cover 5. These may be readily removed and the rings 22 thereupon removed from the casing. If inspection of the pistons is required, the entire barrel 10 with the pistons and rings 22 may be removed in assembled condition and then the parts readily disassembled and inspected. Again, since the parts are self-adjusting and axially floating the dangers of undue tightening of one part relative to another etc. upon re-assembly are eliminated. It is only necessary to insert the barrel and reactances as a sub-assembly and by proper shimming between the cover 5 and end of the casing portion 3a secure the barrel properly in place whereupon the remaining parts will assume a proper operating position free of any binding stresses.

Again, as above explained, the flange and impeller shaft of the barrel 10 are preferably forged integral therewith. Consequently in providing the bearing hubs of the barrel, the barrel valve bore, later to be described, and in polishing the various surfaces, absolute concentricity thereof can be effected, the barrel shaft being utilized as the rotating center during these operations. This again assures absolute concentricity between the barrel shaft and the other finished surfaces so that vibrations occasioned by eccentricity of the shaft or slight angular misalignment thereof are entirely eliminated. Consequently, both efficient production and extreme accuracy are assured.

Referring next to the pressure fluid system and valving relation, the same will be described for purposes of illustration, as that of a transmission embodying the present pump and motor.

In order to effect a proper valving cooperation between the pump and motor, a common valve pintle 50 is provided, the pintle having an enlarged rigid central shank portion 51 fixedly secured in the valve portion 2 of the casing and provided with a main pressure port 52 and diametrically opposite suction port 53. Since the present structure is to operate as a transmission, the outlet of the main pressure port 52 may be blocked with the pressure ducts of the pintle in direct communication and the suction port 53 communicated with a suitable sump.

The pintle 50 extends in each direction from the casing portion 2 in coaxial relationship with the barrels 10 and 30 respectively. Each barrel is provided with a dead end axial bore in which the corresponding end of the pintle is accurately fitted. The protruding end of the pintle associated with the pump is provided with a tapered valve portion 50a having a pressure port 54, and suction or low pressure port 55, with which the cylinder ports 16 successively communicate as the barrel 10 rotates.

The opposite end of the pintle has a valve portion 60a which fits into a correspondingly tapered bore in the barrel 30 and is provided with a pair of pressure ports 60 and suction ports 61, one pressure port and one suction port being provided for each set of cylinders 35.

Pressure ducts 62 are formed in the pintle and connect the main pressure port 52 with the pressure ports 60 of the motor and with the pressure port 54 of the pump. Low pressure or suction ducts 63 in the pintle communicate the main low pressure port 53 with the low pressure ports 61 of the motor and with the low pressure port 55 of the pump, the port 53 being connected to a suitable cooling sump, if desired. Thus a complete pressure fluid circuit is provided. The valve portions of the pintle fit the respective barrel bores with slight but accurate radial clearance, and each valve portion of the pintle is hydrostatically balanced in the manner set forth and claimed in my copending application, Serial No. 754,753, filed November 26, 1934.

For assisting in maintaining the pintle in accurate coaxial relation with positive proper clearance between the pintle and bore of the barrel, annular bearing surfaces are provided at each end of each valve portion of the pintle, and accommodate sets of capillary cageless needle rollers, respectively, such for example as the sets of rollers 64 and 65 of the motor, the details of which are described in my copending applications, Serial No. 641,186, filed November 4, 1932, and Serial No. 23,880, filed May 28, 1935, and which engage radially aligned cylindrical bearing race portions of the barrel bore wall. Instead of true capillary needle rollers, however, larger cageless elongated rollers may be used, but the latter should be spaced a capillary distance from each other circumferentially of the races, as set forth in my copending application, Serial No. 23,880, filed May 28, 1935. In all instances, the main bearings, supporting the barrels, are preferably in radial alignment with the cageless rollers maintaining the pintle in positive coaxial relation with the barrel. The sets of rollers 64 and 65 are sufficiently strong to stress the pintle into true coaxial relation with the barrel in those instances in which inaccuracies in manufacture or assembly would otherwise cause misalignment.

It is apparent from the foregoing description that a highly efficient and simple pump or motor is provided in which the number of working parts has been reduced to a minimum and all parts are so retained that the breakdown of any one part will not necessarily damage the other parts of the pump or motor.

Slip fluid from the cylinders of each structure is forced by centrifugal pressure between the operating faces of the plunger heads, barrel flange, and reactance rings, thus affording lubrication at all times. This fluid finally passes into the recesses of the associated reactance housing which retains it on the rollers therein, forming a circumferentially closed chamber for such fluid. Thus slip fluid is retained by capillary attraction and centrifugal force and provides a combination high pressure oil and anti-friction bearing.

Referring next to Figs. 6 and 7, a novel reactance ring corresponding in function to the rings 22 is illustrated. This reactance ring, designated generally as 75, is one that may be manufactured and assembled readily and in which problems of machining surface, grinding and the like are reduced to simple operations. The reactance ring 75 comprises a pair of coaxial rings 76 and 77.

which are of the same dimensions axially, the ring 77 being of less outside diameter than the inside diameter of the ring 76. In order to space the rings in coaxial relation and to form operating grooves corresponding to the grooves 22a of the ring 22, a number of spacing blocks 78 are provided, these blocks being circumferential segments of a single ring conforming to the clearance space between the rings 76 and 77. The blocks 78 are inserted between the rings and evenly distributed in the circumferentially spaced relation desired, depending upon the number of grooves required and maximum eccentricity of the barrel and reactance, and are secured in place, thus spacing the rings 76 and 77 radially and providing grooves 79 for the ends of the crosspins, as indicated at 80. The blocks 78 are held in place by suitable bolts 81 extending from the inner ring 77 outwardly and cooperating with suitable screw threads in the ring 76.

In order to mount the ring 75 directly on cageless roller or anti-friction structures in the reactance housing, the outer circumferential surfaces of the ring 76 are smooth finished and hardened and the bores in which the bolts 81 are received in the ring 76 terminate radially inwardly from the operating bearing surface of the ring. The reason for inserting the bolts in this manner is that they will be kept in operating position by centrifugal force and looseness and danger of becoming unscrewed will be minimized.

Another modified form of reactance is illustrated in Figs. 8 and 9, wherein rings 83 and 84 corresponding to the rings 76 and 77 are provided. In this structure, however, the rings are free to rotate relative to each other. The inner wall of the ring 83 is provided with annular recesses 85 at each end and the ring 84 is provided with annular recesses 85 at each end and the ring 84 is correspondingly provided on its outer faces at the ends with recesses 86. A ring adapted to fit snugly between the rings 83 and 84 with end portions fitting the recesses is provided and accurately finished. This ring is then cut into the required number of segments 87, which segments are disposed between the rings 83 and 84 and space them a proper distance apart, at the same time forming the grooves 88 for reception of the crosspins of the plungers. The rings 83 and 84 may be disposed in eccentric position with respect to each other and the segments 87, inserted therebetween, whereupon the segments are then generally distributed around the circumference to the desired positions so as to space the rings. This structure has an additional advantage in that upon starting or change of speed of the pump or motor the pins may engage the ends of the blocks 81 and move the blocks slightly circumferentially while maintaining the blocks in the circumferentially adjusted relation with respect to each other. Thus upon starting the pump or motor, the impacts which would otherwise result between the pins and blocks 81 are reduced, due to the fact that the blocks are not fixed to the rings circumferentially but are positioned only by sliding frictional resistance. On continued operation, as the pressure and speed increase, the centrifugal and radial pressure between the pins and reactance exerts sufficient rolling frictional driving engagement for rotating the reactances by the piston pins without the engagement of the crosspins and blocks. As the centrifugal pressure and speed increase, the friction between the blocks 87 and the rings 83 and 84 correspondingly increases until the blocks

are held firmly in position circumferentially, thus providing centrifugal clutches. Consequently, hammering, due to engagement of the crosspins and the blocks 87, is substantially eliminated, and the reactance and barrel are brought to synchronous rotation more gradually. The blocks 87 do not interfere in any manner with the operation after the pump or motor has been brought to its normal speed. Thus a more simple and precise and floating cooperation between the reactance mechanism and the plungers is provided.

In Fig. 10, a one piece ring is used for each reactance ring as in Fig. 4, these rings being designated 90. Each ring 90 is provided with an annular groove 91 extending only part way through the ring axially and opening through the inner end face of the ring. Mounted within the grooves 91 are blocks 92 corresponding in function to the blocks 87 above described. Since the grooves 91, however, are closed at their outer faces, the blocks 92 do not need to be otherwise constrained from outward axial displacement, in which instance, plain annular segments may be disposed in the groove 91 spaced to the position required and thereafter retained in the grooves by the flange of the associated barrel. In this modification, however, the rings are constrained from axial displacement by combination radial load and axial thrust bearings 93. The segmental blocks 78, 87, and 92 may be made of resilient or cushioning material, if desired, for reducing impact noises.

In some instances it is desirable to use pumps and motors employing a single barrel provided with a larger number of sets of circumferentially spaced cylinders and pistons. The present reactance assembly has many advantages when used in such connection. Referring to Fig. 12, there is illustrated a fragment of a barrel 100 having a plurality of circumferentially spaced cylinders 101, each cylinder having a cylinder bore 102 opening into a valve bore 103 of the barrel for cooperation with suitable ports in the valve pintle. Mounted in each cylinder is a plunger 104 having an enlarged head 105 corresponding to the heads 19 of the plunger 18. Each head, in turn, is provided with a bore for receiving the thrust or journal pin 107, common to all aligned plungers, the bore of each piston head being sufficiently large to accommodate capillary rollers 106 for rotatably supporting the pin therein.

It is not uncommon in such structures that the radial hydraulic loads imposed are so great that a plurality of plungers cannot be operated efficiently by a single pin supported only at its ends without an excessively large diameter pin. However, this problem can be solved by supporting the pin at a plurality of portions, for example, both at its ends and intermediate the ends between the plungers. Accordingly, the sets of cylinders may be spaced apart axially of the barrel so that a reactance ring of the present invention may be provided between the sets of pistons as well as at the ends thereof.

Fig. 12 shows a reactance ring arrangement such as shown also on Figs. 8 and 9, including circumferentially adjustable blocks 87 between the inner and outer rings 83 and 86. Instead, the arrangement illustrated in Fig. 12 could employ any other form of reactance rings herein shown or described.

In the form illustrated, the cylinders 101 are spaced apart a sufficient distance so that when the plungers are mounted therein, ample space is provided between adjacent faces of the plunger 18

heads 105 to accommodate a rotary reactance ring which may be made in one piece or may comprise separate ring sections 83 and 86 substantially in accordance with the showing of Figs. 8 and 9, the ring or rings lying in snug engagement between the adjacent faces of the crossheads, operating clearance only being provided therebetween. In addition, rings such as 83 and 86 are provided at the outer end portions 10 of the pin 107 so that the pin is supported throughout its entire length either by the plunger crossheads or the reactance rings. Consequently, the pin can fail only by shearing and dangers of failure or binding, due to bending stresses, are eliminated. Thus the radial load is uniformly distributed axially of the barrel and reactance.

The pin is floatingly mounted in the rollers 106 and is secured in place by suitable snap washers 110 received in recesses in the pin ends in a manner corresponding to the washers 23 of the pin 20. The intermediate rings 83 and 86 are mounted for axial floating movement on free cageless rollers 111 operating in internal circumferential recesses in a common adjustable stationary reactance housing 112, so that in the multi-piston structure, all of the reactance rings and crosshead connections may be self-adjusting axially with respect to each other and to the barrel.

Referring next to Fig. 13, a bearing structure for a reactance ring and having certain distinct advantages is illustrated. It is apparent that in the present types of pumps and motors, when operating at high speed, the roller elements must necessarily rotate at extremely high speeds, and, consequently, cages and retainers cannot be used with safety. To meet this difficulty, capillary cageless rollers or rollers of small diameter, such as set forth in my above identified applications, were used, these operating efficiently because of the elastic cage provided by the capillary oil films between and positively spacing the rollers. The diameter-length ratio of capillary rollers is from 1 to 5 to 1 to 10. In the present large structure, this ratio requirement would necessitate the use of too great a number of needle rollers, would complicate the assembly, and be subject to undesirable pumping effects of the needles. The structure of Fig. 13 may be utilized to advantage when the above diameter-length ratio cannot be fulfilled on account of the limited axial space.

In this structure is illustrated a barrel flange 118 and a pair of reactance rings 119, supported in a reactance housing 120. The housing 120 is provided with internal circumferential recesses 120a. Rollers 122 are accommodated in the recesses for rotatably supporting the rings 119 therein.

The rollers 122 have a greater diameter-length ratio than capillary needle rollers, the ratio of the diameter to the length of the present rollers being about 1:2 and 1:3. The ends of the rollers are square ground, the sharp edges only being bevelled off. Correspondingly the end walls 120b of the recesses 120a are flat and radial, the recesses being substantially equal in radial depth to the diameter of the rollers 122. The end walls 120b of the recesses cooperate with the flat ends 70 of the rollers to positively and accurately guide the rollers, constraining them to substantially fixed axial position and alignment and preventing them from skewing in the recesses or races. Due to the full depth guidance at both ends of the 75 rollers, full lateral guiding is provided, instead of

the guidance afforded by the radial abutment of less than full depth, as in the case of the needle rollers of Fig. 8.

Capillary clearance is provided between the walls 120b and ends of the rollers, this clearance being sufficiently limited to create capillary oil films between the walls and ends of the rollers. For example, such clearance may be from 0.001 to 0.005 of an inch. With capillary clearance provided at the ends and also between the rollers, 10 complete capillary cages are formed for constraining the individual rollers in spaced relation to each other circumferentially of the race. To effect capillary spacing of the rollers from each other, a total circumferential clearance less than the diameter or half the diameter of a single roller is permitted. The bearing assembly is so designed as respect diameter of rollers and pitch diameter that this total circumferential clearance is provided. Consequently, it is absolutely impossible for a workman to pack the rollers circumferentially of the race and thereby prevent the desired individual clearances and rotation of the individual rollers by introducing a roller to fill the total clearance space and thereby eliminate the capillary interspaces.

The total circumferential clearance depends upon the diameter of the rollers, as the total clearance of half to almost a whole diameter of a large roller is equivalent to several needles. 20 Capillary space is limited by other factors and does not vary in proportion to the diameter of the large rollers. Consequently, for the largest rollers, total clearance of about one half roller diameter may be satisfactory whereas, for a smaller 25 roller, larger than a needle, slightly less than full diameter may be provided.

In this manner the rollers are retained in an elastic capillary cage. Such a simplified bearing can be manufactured in the usual machine shop as special equipment, tools, and special skill are not required for its production, and the assembly will operate efficiently at high speeds, for example, at 5000 R. P. M.

Having thus described my invention,

I claim:

1. In a rotary radial plunger pump or motor, a rotatable barrel having a set of circumferentially spaced radial cylinders, valve means for the cylinders, plungers in the cylinders respectively, a rotary reactance eccentric to the barrel, crosspins operatively connecting the rotary reactance and plungers for reciprocating the plungers, said reactance comprising an outer ring, a coaxial inner ring in radial alignment therewith and spaced radially therefrom, a plurality of segmental blocks fitting between the rings and being spaced circumferentially thereof from each other to provide operating grooves, said grooves accommodating the crosspins, and said blocks being slidably circumferentially of the rings for reducing impact forces occasioned between the crosspins and blocks by changes in the relative speed of rotation of the barrel and rings.

2. In a rotary radial plunger pump or motor, a rotatable barrel having a set of circumferentially spaced radial cylinders, valve means for the cylinders, plungers in the cylinders respectively, a rotary reactance eccentric to the barrel, crosspins operatively connecting the rotary reactance and plungers for reciprocating the plungers, said reactance comprising an outer ring, a coaxial inner ring in radial alignment therewith and spaced radially therefrom, a plurality of segmental blocks fitting between the rings and being

spaced circumferentially thereof to provide operating grooves accommodating the crosspins, and said blocks being arranged one between adjacent pins and being slidable circumferentially of the rings.

3. In a rotary radial plunger pump or motor, a rotatable barrel having a set of circumferentially spaced radial cylinders, valve means for the cylinders, plungers in the cylinders respectively, a rotary reactance eccentric to the barrel, crosspins operatively connecting the rotary reactance and plungers for reciprocating the plungers, said reactance comprising an outer ring, a coaxial inner ring in radial alignment therewith and spaced radially therefrom, a plurality of segmental blocks fitting between the rings and being spaced circumferentially thereof to provide operating grooves for the crosspins, and said blocks being slidable circumferentially of the rings for reducing impact forces occasioned between the crosspins and blocks by changes in the relative speed of rotation of the barrel and rings, and cooperating tongues and grooves on the rings and blocks cooperating with the crosspins to retain the rings and associated blocks in assembled condition.

4. In a rotary, radial piston pump or motor, a rotatable barrel having radial cylinders spaced axially of the barrel from each other and having their axes in a common plane through the rotative axis of the barrel, valve means for the cylinders, plungers in the cylinders and having their outer end portions spaced apart axially of the barrel, rotatable coaxial reactance rings eccentric to the barrel and positioned respectively between adjacent outer end portions of the plungers and at the outermost end limits of the plungers axially of the barrel, a thrust pin carried by the outer end portions of the plungers and common to said plungers, said pin being operatively connected to all of said rings for actuating the plungers thereby, means supporting the rings for independent floating movement axially with respect to each other, and means connecting the outermost end portions of the pin to the outermost end ones of said rings for constraining the end rings and pin to proper relative positions to each other and to the plungers axially of the barrel.

5. In a rotary radial plunger pump or motor, a rotatable barrel, a plurality of radial flanges on the barrel spaced apart axially of the barrel from each other, said barrel having rows of radial cylinders, the rows being spaced apart circumferentially of the axis of rotation of the barrel and each row extending parallel to the axis of rotation of the barrel the cylinders of each row being disposed in the zones of the radial flanges, respectively, and having their axes in a common plane through the rotative axis of the barrel, said flanges having radial guideways respective to the cylinders, valve means for the cylinders, plungers in the cylinders and having outer end portions disposed in said radial guideways, respectively, and guided thereby for reciprocation, rotatable, coaxial, independent reactance rings eccentric to the barrel axis and fitting, with operating clearance, snugly between adjacent faces of the flanges and at the outermost faces of the end flanges, respectively, thrust pins for the rows of plungers,

respectively, each pin being common to the outer end portions of all plungers in its associated row and to all of said rings, and each of said pins being operatively connected to all of said rings and its associated plungers for actuating the plungers thereby, and means supporting the rings for independent floating and axial movement with respect to each other.

6. In a rotary radial plunger pump or motor, a rotatable barrel, a plurality of radial flanges on the barrel spaced apart axially of the barrel from each other, said barrel having rows of radial cylinders, the rows being spaced apart circumferentially of the axis of rotation of the barrel and each row extending parallel to the axis of rotation of the barrel the cylinders of each row being disposed in the zones of the radial flanges, respectively, and having their axes in a common plane through the rotative axis of the barrel, said flanges having radial guideways respective to the cylinders, valve means for the cylinders, plungers in the cylinders and having outer end portions disposed in said radial guideways, respectively, and guided thereby for reciprocation, rotatable, coaxial, independent reactance rings eccentric to the barrel axis, and fitting, with operating clearance, snugly between adjacent faces of the flanges and at the outermost faces of the end flanges, respectively, thrust pins for the rows, respectively, each pin being common to the outer end portions of all plungers in its associated row and to all of said rings and each pin being mounted in the outer end portions of all the associated plungers and the rings for rotation about its own axis and relative to the barrel, and each of said pins being operatively connected to all of said rings and its associated plungers for actuating the plungers thereby, and means supporting the rings for independent rotation with respect to each other.

7. In a rotary radial plunger pump or motor, a rotatable barrel, a plurality of radial flanges on the barrel spaced apart axially of the barrel from each other and having radial end faces, said barrel having rows of radial cylinders, valve means for the cylinders, each row of cylinders extending axially of the barrel and the rows being spaced circumferentially of the barrel from each other, the cylinders of each row being arranged at the zones of the flanges respectively and having their axes in a common plane through the rotative axis of the barrel, radial guideways in said flanges and aligned with the cylinders respectively, radial plungers in the cylinders respectively and having outer end portions spaced apart axially of the barrel and reciprocable in the guideways of the associated flange, rotatable coaxial independent reactance rings eccentric to the barrel and respectively snugly fitting with operating clearance between the radial end faces of the flanges and between adjacent outer end portions of the plungers and against the radial faces of the flanges at the outermost end limits of the row of plungers axially of the barrel, thrust pins respective to the rows of plungers, each crosspin being carried by and common to the outer end portions of all of the plungers of the associated row, and each pin being operatively connected to all of said rings for actuating the plungers thereby.

ELEK K. BENEDEK.
